GARMENT PRESSING MACHINE

Angus F. Hanney, Norwood, Ohio, assignor to
 The American Laundry Machinery Company,
 Cincinnati, Ohio, a corporation of Ohio

Application August 5, 1933, Serial No. 683,814

14 Claims. (Cl. 68—9)

This invention relates to a control mechanism for pressing machines such as are used in the pressing of garments and laundry work.

One of the objects of my invention is to provide a simple control mechanism whereby the operator moves one control member and thereafter the other movements for the closing of the press take place automatically.

Another object of the invention is to provide a second control member which acts as a guard to prevent injury to the operator's hands during the closing of the press, and which is actuated by the operator for the normal opening operation.

Another object of the invention is to provide simple controls for cross or tandem operation of two presses, whereby the movement of a control member for one press causes the opening operation of the other press.

A further object of the invention is to provide one control member having two positions, the first of which controls the press for individual operation and the second of which controls a second press in tandem operation.

A further object of the invention is the provision of simple automatic means for exhausting moisture from the pressing bed.

Other objects and advantages of the mechanism will be obvious from the following description of the drawings and specification, and the essential features of which are summarized in the claims. In my copending divisional application Ser. No. 705,279, filed January 4, 1934, will be found claims relating to the means for exhausting moisture from the pressing bed and for creating a fluid flow therethrough.

In the drawings, Fig. 1 is a side view of a pressing machine somewhat diagrammatic in form which shows an embodiment of my invention; Fig. 2 is a view of the release cylinder and operating parts associated therewith; Figs. 3, 4 and 5 are fragmentary views along the corresponding numbered lines of Fig. 1; Fig. 6 is an enlarged sectional view of the pressing bed or buck along the line 6—6 of Fig. 7; Fig. 7 is a partial sectional view of the buck along the line 7—7 of Fig. 6; while Fig. 8 is a side elevation somewhat diagrammatic in form showing two presses connected for cross or tandem operation.

I have chosen to illustrate my control mechanism as applied to a press of the type disclosed, described and claimed in the co-pending application of John P. Singiser, Ser. No. 683,322, filed August 2, 1933, although it will be understood that the mechanism is applicable to any pressing

machine having coacting relatively movable pressing elements.

A complete description of the construction and operation of the press here illustrated will be found in the above mentioned application and only sufficient description will be given here to permit an understanding of the operation of the control mechanism. The press comprises a suitable frame 10 supporting two coacting pressing members, a head 11 and a bed or buck 12, the head being supported in fixed position and the bed being supported on a carriage 13 equipped with rollers 14 which travel on rails 15 permitting the buck to have a translatory motion in a substantially horizontal direction from and into registering position beneath the head. The bed is provided with a stem 16 extending downwardly in a bearing 17 of the carriage which permits a limited vertical movement of the bed with respect to its carriage. Translatory movement of the bed is provided by a fluid pressure operated translation motor comprising a cylinder 18 having a suitable piston 19 and a piston rod 20. The piston rod is connected to the buck carriage by link 21, cranks 22 and 23 pivoting about the shaft 24, and link 25 connected to the carriage. As viewed in Fig. 1, movement of the piston 19 to the right will move the bed 12 into registering position beneath the head. The return movement of the bed to its outer or open position is caused by spring 26 connected by crank 27 to the shaft 24.

When the pressing members are in registration, the bed is raised substantially vertically from its carriage and is pressed against the head by a second fluid motor comprising a piston 28 in a cylinder 29 mounted on the frame beneath the head. This motor is hereinafter referred to as the reciprocation motor. The piston rod 30 contacts the stem 16 thus raising the bed.

The control mechanism comprises, in general, inlet and outlet valves for the control of the flow and exhaust of fluid pressure to and from the translation motor, and these valves are operated by a control member having an operating handle conveniently positioned for the operator. Normal movement of this control handle closes the outlet and opens the inlet valve admitting fluid pressure to the translation motor, which causes the bed to move into registering position with the head. Suitable devices, actuated by the movement of the bed into registering position, cause movement of the control valves for the reciprocation motor, thus causing the press to close. The movement of the control valves for both motors in press-opening direction is caused by

release means operated by fluid pressure from the main supply line. The control valve for the release means is actuated by a swinging guard depending before the head in a position to be struck by the operator's hands if they are resting upon the buck as it moves toward its pressing position. In this case, the guard operates as an emergency release member, but in the regular operation of the press also, movement of the guard rearwardly is utilized to actuate the control valves to open the press.

In Fig. 1 the exhaust valve 31 and the inlet valve 32 for the cylinder 18 of the translation motor are operated by cam 33 mounted on the oscillatable control shaft 34 having a control handle 35. Normal movement of the control handle to position 35A (Fig. 3) closes valve 31 and opens valve 32 which admits fluid pressure from the main supply line through conduit 77 to cylinder 18 thus causing translatory movement of the bed into registration with the head. 36 is the exhaust valve and 37 the inlet valve for cylinder 29. They are operated through lever 38, link 39, bell crank 40, link 41, bell crank 42, link 43 and interlock arm 44 which carries a follower 45 which in turn presses against a cam 46 mounted on the carriage 13. A notch 47 will be noted in the cam 46 and when the bed reaches registering position, the follower 45 moves into the notch 47 impelled by a spring 48 acting through bell crank 42 and its attached linkage so that the interlock lever moves in a clockwise direction. This moves bell crank 40 in a like direction and moves link 39 to the right, which closes the valve 36 and opens the inlet valve 37 admitting pressure from the main pressure supply conduit through conduit 90 to cylinder 29. Piston 28 rises and its rod 30 contacts stem 16 of the bed, causing reciprocatory movement of the bed toward the head.

For opening the press, power operated means is provided for reversing the position of valves 31 and 32 and also of valves 36 and 37. The means illustrated comprises a release cylinder 49 supplied with a suitable piston and rod 50 which in the releasing operation moves upwardly contacting an arm 51 pivoted at 52 to the frame and having an oppositely extending arm 53 rigid therewith. This construction is more clearly seen in Fig. 2, where the shaft 34 is shown provided with a flanged collar 54 adapted to be contacted by the arm 51 as it moves upwardly. The position of collar 54 when the control lever has been moved in the press closing position is shown in broken lines, Fig. 2 and the movement of the lever 51 upwardly returns the collar to the full line position, thus closing inlet valve 32 and opening outlet valve 31 and exhausting the fluid pressure from cylinder 18. Spring 26 is then effective to move the bed to its outer position. Referring again to Fig. 2, the end of lever 53 is loosely mounted to the upper portion of the rod assembly 41 in a lost motion connection in the form of a slot 55. When the rod 41 is elevated, by operation of the interlock arm 44 in clockwise direction as above described, the rod 41 moves upwardly without any effect on the position of lever 53, but pin 56 of the lever comes into approximate engagement with the lower end of slot 55. Thereafter, when fluid pressure moves lever 51 upwardly, lever 53 at the same time moves downwardly, moving the rod assembly 41 downwardly which causes closing of the inlet valve 31 and opening of the outlet valve 36, thus exhausting cylinder 29. The piston 28,

rod 30 and bed 12 move downwardly due to the weight of the parts.

The supply of fluid pressure to release cylinder 49 is controlled by release valve 57 which communicates with the main pressure supply line 5 through conduit 51'. The release valve is actuated by engagement of its stem with contact arm 58 which abuts the guard 59 in its freely depending position before the head. Movement of the guard 59 rearwardly opens valve 57 admitting 10 pressure to cylinder 49 through conduit 60. This actuates piston and rod 50 as above described. A check valve 61 prevents flow of fluid pressure beyond that point.

For cross or tandem operation of two presses, 15 an extra air valve is provided on one press which is actuated simultaneously with the admission of pressure to the translation motor of that press and admits air to the release cylinder of a second press, thereby causing the second press to open 20 so that it is ready for the operator by the time she has moved from one machine to the other. The arrangement shown comprises a valve 62 mounted in line with valves 31 and 32 and adapted to be actuated by a cam 63 mounted on the 25 shaft 34. The cam has a projecting portion 63' shown in Figs. 1 and 4. Ordinarily, this cam 63 is not moved sufficiently for projection 63' to actuate valve 62 when the control handle 35 is moved normally to actuate the press for individual operation. This is more clearly shown in Fig. 3 where 35A is the first or normal position of the control handle corresponding to individual press operation, to which position it is moved to actuate only cam 33 controlling the valves 35 31 and 32. The second or abnormal or tandem position 35B is the position to which the handle is moved to rotate cam 63 just sufficiently to cause projection 63' to actuate valve 62. Valve 62, being open, admits fluid pressure from the 40 main pressure supply through conduit 64, through valve 62 and conduit 65 which communicates with the release cylinder 49 of the second press. I have thus provided a very simple control for either individual press operation or tandem operation. The operator need learn but two positions of a single control handle.

I have also provided a bed or buck which is arranged for the automatic exhaustion of moisture from the interior thereof. This bed or buck 50 comprises in general a hollow member with a bottom sloping to a common drainage point, and having upstanding ribs 70 extending longitudinally of the buck upon which lies a heavy wire fabric 71 for supporting the covering or padding 55 of the buck. The ribs have passages 72 therethrough adjacent the sloping bottom 73 which leads to a flexible discharge conduit 74 which is automatically connected for discharge of the moisture contents in the lower part of the bed 60 upon completion of the pressing operation. Suction for this moisture exhausting operation is provided by utilizing the exhaust from one of the fluid motors which moves the buck toward the head. To this end, the outlet conduit 75 from 65 exhaust valve 31 of the translation motor is connected to an ejector arrangement 76 so that upon opening the outlet valve 31 to open the press, the fluid exhausting from cylinder 18 will pass through conduit 77, valve 31, conduit 75, and 70 ejector 76, causing a suction in conduit 78. This conduit communicates with a coupling member 79 mounted on the frame of the press in a position to coact with a similar member 80 on the bed connected with the discharge conduit 74, thus 75

causing the evacuation of the moisture from beneath the bed through the ejector 76. This moisture is thrown against a heated element 81 which evaporates it so that it passes into the atmosphere.

The structure illustrated for the coupling members 79 and 80 is clearly shown in Fig. 1. The member 80 has a projection 82 mounted for limited horizontal movement in a guide 83. The member 10 is spring-pressed toward member 79 by a spring 84. A ball-check valve 85 normally closes the outlet from conduit 74. When the pressing members are in pressing position, a plunger 86 moves valve 85 from its seat, thus establishing communication between conduits 74 and 18.

This moisture exhausting mechanism will operate whether the moisture is substantially all vapor, or substantially all condensate, or a mixture of vapor and condensate. The buck illustrated in Figs. 6 and 7 is a cold buck and will condense part or substantially all of the entering vapor depending on working conditions. The covering or padding of the buck is, of course, porous. Moisture from the work lying on the buck is converted into vapor by heat from the pressing head and passes into the interior of the hollow buck. There it is condensed and passes out through conduit 74, coupling members 80 and 79, and conduit 18 drawn by the suction created by ejector 76, which in turn throws the condensate against heated element 81, which evaporates it so that it passes into the atmosphere.

The operation of a single press is as follows:

The operator arranges the lay of the work on bed 12 and moves the control handle 35 to its first or normal position 35A.

Thereupon cam 33 closes valve 31 and opens valve 32 admitting fluid pressure from the main supply conduit through conduits 64 and 77 to cylinder 18, thus moving piston 19 forwardly and, through the connecting linkage, causing bed 12 to move rearwardly into registering position beneath the head 11. When the pressing members reach registering position, interlock arm 44 moves clockwise when follower 45 moves into notch 47 of cam 46 under the influence of spring 48. This interlock arm through connections 43, 42, 41, 40 and 38 actuates lever 38 to close valve 36 and open valve 37, thus admitting fluid pressure from the main supply conduit through conduit 90 to cylinder 29. Piston 28 and rod 30 are raised, contacting stem 16 and raising bed 12 into pressure engagement with head 11. Upon completion of the pressing operation, the operator swings guard 59 rearwardly which, through contact arm 56, opens valve 51, thus admitting fluid pressure from the main supply conduit through conduits 57' and 60 to release cylinder 49. Release piston rod 50 raises lever 51 into contact with flanged collar 54, returning it to its original position, whereby cam 38 closes valve 32 and opens valve 31, thus exhausting cylinder 18 of the translation motor and permitting spring 26 to return the bed to its forward open position. Simultaneously with the actuation of lever 51 by the release piston rod, lever 53 through pin 56 moved link 41 downward and, through bell crank 49, link 39 and lever 38, caused valve 37 to close and valve 36 to open, thus exhausting the pressure from cylinder 29 of the reciprocation motor, whereupon the piston 28, piston rod 30 and bed 12 moved downwardly due to the weight of the parts. If the operator's

hand or arm lies on the bed as it moves to registering relation with the head, it engages the guard and emergency release operation occurs in exactly the same manner as the normal release operation just described.

When fluid pressure was exhausted from cylinder 18 through the opening of valve 31, the exhaust fluid passed through conduit 75 and ejector 76, causing a suction in conduit 18, which through coupling members 79 and 80 which were then in close contact caused evacuation of moisture through discharge conduit 14, connected with the interior of the hollow buck.

For tandem operation, the operator arranges the lay of the work on bed 12 and moves the control handle 35 to its second or abnormal tandem position 35B, which causes the operation of the first press as before described, and in addition, cam 63 rotates sufficiently to cause projection 63' to open valve 62, thus admitting fluid pressure from the main supply conduit, through conduits 64 and 65 to the release cylinder 49a of a second press to open that press.

The arrangement of two presses for tandem operation is illustrated somewhat diagrammatically in Fig. 8, where the parts of the second press are numbered to correspond with the description of the first press except that they carry the suffix "a".

What I claim is:

1. In a press of the class described, a frame, coacting pressing members, one of which is movable relative to the other, power mechanism for actuating the movable member, control means for said mechanism, power means for actuating said control means in press-opening direction, a finger guard mounted on a fixed portion of the frame adjacent the path of travel of said movable member, and a control member for said power means operable by said finger guard.

2. In a press of the class described, the combination of, coacting pressing members, one of which is movable toward the other, a fluid motor for actuating the movable member, control valves for said motor, cam means freely movable into different positions in which it will remain until again moved, means for moving said cam means in one direction for actuating said valves in press-closing direction, and a fluid pressure actuated release member for moving said cam means in the opposite direction.

3. In a press of the class described, coacting pressing members, one of which has translatory motion into and out of registration with the other and pressure-producing motion with respect to the other to close and open the press, a fluid motor for causing each motion, control valves for each motor, a cam-carrying control shaft for actuating the control valves for the translation motor in into-registration direction, interlocking mechanism for actuating the control valves for the pressure-producing motor in press-closing direction after the translation motor has moved the members to registering position, and a common release member for simultaneously moving said control valves in press-opening and out-of-registration direction.

4. In presses of the class described, a plurality of machines each having coacting pressing members, one of which is movable toward the other, power means for actuating the movable member, and control means for said power means; and each press having a control member having one cam for moving said control means of the first

- press in press-closing-producing direction, and said control member having a second cam for moving said control means of a second press in press-opening-producing direction.
5. In presses of the class described, a plurality of machines each having coacting pressing members, one of which is movable toward the other, a fluid motor for actuating the movable member, inlet and exhaust valves for said motor, a control member having one position for actuating said valves in one direction, and a fluid-pressure-actuated release member for actuating said valves in the opposite direction, and said control member of one machine having a second position for actuating the release member of another machine.
6. In presses of the class described, a plurality of machines each having coacting pressing members, one of which is movable toward the other, a fluid motor for actuating the movable member, inlet and exhaust valves for said motor, an oscillatable control member having a cam for actuating said valves in one direction, a fluid-pressure-actuated release member for actuating said valves in the opposite direction, and said control member of one machine having a second cam for actuating the release member of another machine.
7. In a press of the class described, the combination of coacting relatively movable pressing members, fluid pressure actuated power means for moving one of said members, control valves therefor, fluid pressure actuated release means for a second press, a control valve therefor, all of said control valves being actuated by a common actuator having one position for operating the first-mentioned control valves, and a second position for operating the last-named control valve.
8. In a press of the class described, a stationary head, a bed having a translatory movement from and into registration with the head and a pressure-producing movement toward the head, a finger guard depending before said head and adjacent the path of travel of said bed during its translatory movement, two fluid motors for causing said bed movements, inlet and outlet valves for controlling the flow and exhaust of fluid pressure to and from said motors, a control member movable into one position for actuating the valves of the translation motor in into-registration direction, interlocking means arranged to cause actuation of the control valves for the pressure-producing motor in press-closing direction when the bed is in registration with the head, fluid pressure actuated release means for moving the valves of both motors in press-opening and out-of-registration direction, a release valve for controlling the flow of pressure to the release means, said release valve being operable by movement of said finger guard, a tandem valve for admitting fluid pressure to the release means of a second press, and said tandem valve being operable by movement of the control member to a second position.
9. In a press of the class described, the combination of coacting relatively movable pressing members, a fluid motor for actuating one of said members, control valves for said motor, an oscillatable shaft freely movable into different positions in which it will remain until again moved, cams on said shaft for operating said control valves when said shaft is oscillated, a servo-motor, a fluid pressure supply for said servo-motor, control means therefor, manual means for moving said shaft in one direction, and an operative connection between said shaft and said servomotor for moving said shaft in the opposite direction.
10. In a press of the class described, coacting pressing members, one of which is movable substantially horizontally into and out of registration with the other, power mechanism for actuating the movable member, control means for said mechanism, a power operator for moving said control means in out-of-registration-producing direction, a guard movably mounted independently of said movable member and adjacent the path of travel of said movable member, and means having an operative connection with said guard for actuating said power operator when said guard is moved in the general direction of said into-registration movement.
11. In a press of the class described, coacting pressing members, one of which is movable substantially horizontally into and out of registration with the other, power mechanism for actuating the movable member, control means for said mechanism, a fluid motor for moving said control means in out-of-registration-producing direction, a normally closed valve for inlet of motive fluid to said motor, a guard movably mounted independently of said movable member and adjacent the path of travel of said movable member, and means having an operative connection with said guard for opening said valve when said guard is moved in the general direction of said into-registration movement.
12. Two presses of the class described, each press having a pair of coacting relatively movable pressing members, power means at each press for causing relative movement between the pressing members thereof to close and open each press, control mechanism for each power means, a single control member at each press, each control member having two positions, an operative connection between each control member in one of its positions and the control mechanism of the associated press for causing closing of that press, and operative connections between each control member in the other of its positions and the control mechanisms of both presses, one of said last named connections being effective to cause press-closing operation of the associated press, the other of said last named connections being effective to cause press-opening operation of the other press.
13. Two presses of the class described, each press having a pair of coacting relatively movable pressing members, power means at each press for causing relative movement between the pressing members thereof to close and open each press, control mechanism for each power means, a power device for moving each control mechanism in a manner to cause press release operation of its associated power means, a single control member at one of said presses, said control member having two positions, operative connections between said control member in each of its positions and the control mechanism of its associated press for causing closing of that press, and an operative connection between said control member in one of its positions and the power device of the other press for causing operation of said device.
14. Two presses of the class described, each press having a pair of coacting relatively movable pressing members, fluid actuated power means at each press for causing relative movement between the pressing members thereof to close and

open each press, fluid supply means for each power means including control valves at each press, a fluid actuated servo-motor at each press for causing actuation of the associated valves in press-re-
lease-producing direction, a control member at one of said presses, said control member having two positions, means whereby said control mem-

ber in each of its positions causes press-closing-producing movement of the control valves for said power means at the said one press, and means whereby said control member in one only of its positions causes actuation of said servo-motor at the other of said presses. 5

ANGUS F. HANNEY.
